CLAIM

The ornamental design for a three-wheeled vehicle, as shown and described.

DESCRIPTION

FIG. 1 is an upper front perspective view of a three-wheeled vehicle.

FIG. 2 is a lower rear perspective view showing the design of FIG. 1.

FIG. 3 is another lower rear perspective view showing the design of FIG. 1.

FIG. 4 is a lower front perspective view showing the design of FIG. 1.

FIG. 5 is a right side view showing the design of FIG. 1.

FIG. 6 is a left side view showing the design of FIG. 1.

FIG. 7 is a front view showing the design of FIG. 1.

FIG. 8 is a rear view showing the design of FIG. 1.

FIG. 9 is a top view showing the design of FIG. 1; and,

FIG. 10 is a bottom view showing the design of FIG. 1. The broken lines are used for the purpose of illustrating portions that form no part of the claimed design.

1 Claim, 10 Drawing Sheets
